UNITED STATES PATENT OFFICE.

WILLIAM GORDON PARMELE, OF SEATTLE, WASHINGTON.

PADLOCK.

Application filed April 21, 1923. Serial No. 633,811.

To all whom it may concern:

Be it known that I, WILLIAM G. PARMELE, a citizen of the United States, residing at Seattle, in the county of King and State of Washington, have invented a new and useful Padlock, of which the following is a specification.

This invention relates to a padlock, the principal object being to provide a padlock which will completely house and conceal the projecting portion of the staple or keeper so as to prevent unauthorized access thereto.

Another object is to provide a padlock the housing of which is so shaped as to prevent the same from being turned readily, as when an attempt might be made to twist the staple or keeper out of position.

Another object is to provide a padlock simple, durable and compact in construction, formed of few parts and being easy to apply.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit of the invention as claimed.

In the accompanying drawings the preferred form of the invention has been shown.

In said drawings:

Figure 1 is a perspective view showing the padlock applied.

Figure 2 is an inverted perspective view of the padlock.

Figure 3 is a longitudinal section through the padlock in engagement with a staple.

Figure 4 is a section on line 4—4 Figure 3.

Figure 5 is a section on line 5—5 Figure 3.

Figure 6 is a section on line 6—6 Figure 3.

Referring to the figures by characters of reference 1 designates the housing of the padlock, the same being formed preferably in one piece substantially semiellipsoidal in contour. Formed in the base of this housing is a diametrical groove 2 extending partially across the same and closed at its ends. A passage 3 extends inwardly from one end of this groove and communicates with a compartment 4. One wall of this compartment may be grooved longitudinally as

shown at 5 while the opposite wall is preferably formed with an oblique portion 6 terminating in a shoulder 7 located at the inner end of the passage 3. An opening 8 extends into the housing 1 from the small or apex portion thereof and opens into the compartment 4. In this opening is secured a tumbler mechanism indicated generally at 9 designed to cooperate with a key 10 inserted into the lock. Obviously unless the key is of the proper size and contour it cannot be inserted into the lock and rotated.

A bolt 11 is normally seated within groove 2 so as to completely fill the same and lie flush with the base of the housing. Extending from one end of this bolt is an arm 12 and this arm projects through passage 3 into compartment 4 and normally bears against the end wall of the compartment. A longitudinal rib 13 is formed on the arm and is adapted to slide in groove 5, thus to limit the movement of the arm.

Mounted in the compartment 4 is a block 14 constituting a tumbler and one corner portion of this block is cut away diagonally as shown at 15 so as to ride on the wall 6 of the compartment. V-shaped teeth 16 project from the tumbler 14 and corresponding recesses 17 are formed in the arm 12. A spring 18 bears against tumbler 14 and also against the housing and serves to press the tumbler so that it will wedge between wall 6 and arm 12. Teeth 16 will also act as wedges and when pressed laterally into recesses 17 will tend to draw the bolt 11 back into recess or groove 2.

One end of the tumbler 14 has a recess 19 partly closed to provide a key receiving slot 20. Key 10 has a lug 21 projecting laterally from its free end and this lug is adapted to be inserted through slot 20. By then turning the key the lug can be interlocked with the tumbler 14, as shown in Figure 3.

In the drawings a hasp has been shown at H and a staple or keeper has been indicated at S. Groove 2 has lateral extensions 22 as shown in Figure 2 and these extensions cooperate to provide a recess sufficiently large to receive the staple S. Assuming that the bolt 11 is supported outside of the groove 2 as shown in Figure 2, it can be inserted into the staple S. By then pushing housing 1 toward the staple the bolt 11 will be thrust into groove 2 and the recessed edge of arm 12 will slip past teeth 16. Thus the relative

movement of the housing, arm 12 and bolt 11 will be along lines extending axially of the housing. During this operation tumbler 14 will be thrust toward opening 8, thereby compressing spring 18. As soon as the staple has been properly seated in the housing the lock can be released. Spring 18 will thrust tumbler 14 against wall 6 and this wall will deflect the tumbler so as to cause its teeth 16 to wedge into recesses 17. Consequently bolt 11 will be held securely in groove 2 and any attempt to pull the housing off of the staple would merely result in more tightly wedging tumbler 14 in position. Because of the peculiar shape of the housing it cannot be gripped readily and it would therefore be difficult to force it off of the staple. To remove the lock a key of proper size and shape is inserted into the lock and into slot 20 and then rotated. The key will thus hook into tumbler 14 and by pulling the key outwardly it will draw the tumbler with it, thereby releasing arm 12 and allowing the housing 1 to be pulled outwardly a sufficient distance to permit the bolt 11 to be withdrawn from the staple.

What is claimed is:

1. A padlock including a housing having a recessed staple receiving base, a staple engaging bolt normally seated in the recess, an arm extending from the bolt, said arm and bolt being shiftable axially of the housing in one direction to draw the housing onto the staple and in the opposite direction to release the staple from the housing, a tumbler having wedging engagement with the housing and arm for holding the bolt in normal position, said member being movable axially of the housing, yielding means for holding the tumbler in wedging position, and means for engaging the tumbler to release the arm.

2. A padlock including a housing having a recessed staple receiving base, a bolt normally seated in the base for engaging the staple to hold the staple concealed in the housing, a recessed arm extending from the bolt and slideable in and axially of the housing, a wedging tumbler cooperating with the housing and arm to secure the bolt against outward movement and to exert an inward pull upon the bolt and maintain the housing substantially fixed relative to the

engaged staple, yielding means for holding the tumbler in wedging position, and key 55 engaging means on the tumbler for actuation of the tumbler by an inserted key.

3. A padlock comprising a rounded housing having a flat recessed base for the reception of a staple, a bolt diametrically disposed relative to the housing and normally seated in the base in engagement with a staple, an arm extending from the bolt into the housing having a side recess, said arm and bolt being movable axially of the housing, a wedging tumbler movably mounted in the housing, a laterally extending tooth thereon for wedging engagement with the recess in the arm, yielding means in the housing for holding the tumbler normally in 70 wedging position, thereby to maintain the housing substantially fixed relative to the engaged staple and means on the tumbler for engagement by a releasing key.

4. A padlock including a rounded housing 75 having a flat recessed staple receiving base, a bolt normally seated in the recess, an arm extending from the bolt into the housing and movable axially of the housing, spring pressed wedging means in the housing for holding the bolt against withdrawal and for exerting a constant inward pull upon the bolt, to maintain the housing substantially fixed relative to an engaged staple and means carried by said wedging means for 80 engagement by a releasing key.

5. The combination with a staple and a member to be secured thereto, of a housing having a flat staple receiving base adapted to be supported outside the housing for insertion into a staple, said housing being shiftable relative to the bolt and house the bolt and the engaged portion of the staple, and cooperating wedging means on the bolt and in the housing for holding the bolt 95 against withdrawal from the housing and for binding the housing against said member.

In testimony that I claim the foregoing as my own, I have hereto affixed my signature 100 in the presence of two witnesses.

WILLIAM GORDON PARMELE.

Witnesses:

Mrs. ANNIE Post,
IRA JACKSON.
